The ornamental design for a dual field coil eddy current brake, as shown and described.

DESCRIPTION

FIG. 1 is a perspective view of a dual field coil eddy current brake showing my new design;

FIG. 2 is a perspective view in different angle thereof;

FIG. 3 is a front elevation view thereof;

FIG. 4 is a rear elevation view thereof;

FIG. 5 is a left elevation side view thereof;

FIG. 6 is a right elevation side view thereof;

FIG. 7 is a top plan view thereof; and,

FIG. 8 is a bottom plan view thereof.
